UNITED STATES PATENT OFFICE.

JOHN O. BURKLUND, OF WORCESTER, MASSACHUSETTS, ASSIGNOR OF ONE-THIRD TO
PEHR G. HOLMES, OF WORCESTER, MASSACHUSETTS.

BALL-CONTAINER FOR BALL-BEARINGS.

1,222,927.

Specification of Letters Patent. Patented Apr. 17, 1917.

Application filed May 9, 1916. Serial No. 96,441.

To all whom it may concern:

Be it known that I, JOHN O. BURKLUND, a citizen of the United States, residing at Worcester, in the county of Worcester and 5 Commonwealth of Massachusetts, have invented a new and useful Improvement in Ball-Containers for Ball-Bearings, of which the following is a specification accompanied by drawings, forming a part of the same.

10 The object of my present invention is to provide a container for holding balls in a ball bearing, capable of being constructed from a single piece of sheet metal, and of holding the balls properly spaced within 15 the bearing, and enabling the balls to be removed with the container without change of position.

Referring to the accompanying drawings, Figure 1 represents one of my containers 20 having balls inclosed therein, and detached from the ball bearing.

Fig. 2 represents a blank from which the container is constructed, as hereinafter described.

25 Fig. 3 represents the blank having a series of concave recesses formed for the reception of the balls.

Fig. 4 is an edge view of a portion of the blank showing three of the ball receptacles 30 open in position to receive the balls.

Fig. 5 is an edge view of the container in its completed form.

Fig. 6 is a transverse sectional view through one of the ball receptacles, showing 35 a ball held therein.

Fig. 7 is a sectional view through the container, on the plane of the broken line 7—7, Fig. 5.

Fig. 8 is a longitudinal sectional view 40 through one of the ball receptacles, showing a ball held therein.

Similar reference characters refer to similar parts throughout the different figures.

The blank from which my ball container 45 is formed is punched from a single piece of sheet metal, as represented in Fig. 2, and it consists of an annular band 1 having projecting from the outer edge thereof a series of wing pieces 2. At the ends of the wing 50 pieces and extending laterally therefrom are prongs 3, 3, for the purpose hereinafter described. The blank form, as represented in Fig. 2, is then shaped by appropriate punches and dies into the form shown in 55 Fig. 3, in which the annular band 1 is

stamped at regular intervals to form a series of concave recesses 4, and the wing pieces 2 are similarly shaped to form a recess 5 for the ball.

During this operation of forming the recesses 4 and 5 the prongs 3, 3, are turned down at right angles to the wing pieces 2. The wing pieces 2 are next folded on the broken lines 6 against the side of the annular band 1. The wing pieces are then bent 65 so they stand at right angles to the annular band 1, as represented in Fig. 4. When the balls have been placed in position in the recesses 4, the wing pieces 2 are bent over the balls, as shown in Fig. 5, each ball being 70 held in the space inclosed by the recessed portions 4 and 5, with the prongs 3 extending over the edges of the annular band 1. The tips of the prongs are then turned down against the annular band, as shown 75 at 7, Fig. 7.

Each of the balls is then inclosed in a cage formed by the recesses 4 and 5. The width of the recessed portions 4 and 5 being greater than the diameter of the balls, causes the 80 balls to be held therein and to slightly project, as shown at 8, 8, Figs. 1 and 6, beyond the edges of the holder so as to bear upon the opposite faces of the ball track.

My improved container is not only made 85 from a single piece but is constructed with but few operations, and avoids the necessity of separately riveting the pieces together.

I claim,

1. A ball container, formed from an integral blank and comprising an annular band having wing pieces connected at one end to the outer edge of said band, said annular band having a series of concave recesses, and each of said wings having a concave recess midway between its ends, with said wings bent against said band to bring said recesses in opposition to the recesses in said band to provide ball spaces. 90

2. A ball container formed from a single 100 piece of sheet metal and comprising an annular band having wing pieces integral with its outer edge and provided at their free ends with laterally extended prongs, said wing pieces being folded against said band and having their prongs extended over the edge of said band, said band and said wing pieces having curved recesses to provide ball spaces. 105

3. A ball container, comprising an annu- 110

lar band having a series of spaced recesses, wing pieces integral at one end with said band, and means for uniting the opposite ends of said wings with said annular band.

5. 4. A ball container comprising an annular band, having wing pieces extending from its outer edge and connected at their free ends with said band, and concave recesses in said band and in said wing pieces form-

ing spherically shaped receptacles for the reception of balls, said receptacles having openings to permit the contact of the balls with ball tracks.

Dated this fourth day of May 1916.

JOHN O. BURKLUND.
